VENEER LATHE

Application filed June 25, 1929. Serial No. 373,509.

This invention relates to a veneer lathe, and more particularly to the driving mechanism for the log spindles thereof and to the controlling means for such mechanism.

In the operation of veneer lathes and the production of veneer strips thereby, a disadvantage has existed in that the veneer strip is cut from the rotating log more rapidly at first while the log diameter is relatively large, than it is later after the log diameter has been diminished in size. In other words, the veneer strip comes off the outer circumference of the log rapidly, but steadily diminishes in speed until when the core of the log is reached the veneer strip is produced very slowly.

The principal object of the present invention is to provide a veneer lathe capable of cutting a veneer strip from a log at a constant rate of production irrespective of the log diameter.

Another object is to provide in a veneer lathe, means for automatically controlling the driving means for the log spindles, so that the rate of rotation of the log supported by the spindles will vary in a predetermined ratio to variations in the log diameter.

A more specific object is to provide in a veneer lathe means for automatically controlling the driving means for the log spindles, so that the rate of rotation of the log supported by the spindles will be accelerated in the proper proportion to the diminution of the diameter of the log as the veneer strip is cut therefrom.

Another object is to provide a drive for a veneer lathe, whereby the lathe will always produce veneer at constant speed, and one which may be instantaneously controlled for quick stopping, quick reduction in speed and rapid rotation for rounding up the log.

Another object is to provide a drive for a veneer lathe and a controlling means therefor, which is inexpensive, requires a minimum amount of space, may be readily installed on lathes already in use, and wherein the speed of operation of the driving means is independent of the load.

Additional objects and advantages will be

come apparent hereinafter, as the description of an embodiment of the invention proceeds.

In accomplishing the above objects the invention, in its broader aspects, contemplates the provision, in a veneer lathe, of means for automatically increasing in the proper ratio or amount the speed of rotation of the log as the diameter thereof decreases, whereby the veneer strip will be cut always at a constant rate, irrespective of log diameter, and to employ as a driving means for the log spindles which support the log and effect its rotation, a driving element having a constant operating speed, irrespective of load, and capable of being controlled for quick stopping, quick deceleration, and quick acceleration, for rounding up the log when necessary.

More specifically, the invention contemplates the employment of a shunt wound direct current motor as the driving means for the log spindles, and the control of the speed of operation of such motor by means of a rheostat, which, in turn, is automatically operated in direct relationship to the reduction in diameter of the log supported by the spindles.

Before proceeding with the detailed description of a particular embodiment of the invention, and in order that the advantages inherent in the present invention will be apparent at once, it will be advisable to set forth briefly the attempts which have been made heretofore to control the operation of the driving means for the log spindles with a view of obtaining a constant cutting rate for the veneer strip irrespective of log diameter variations.

Among the different attempts to obtain this result, the oldest was the employment of the double clutch pulley, which provided two distinct speeds of rotation for the log. The low speed was used on large logs, and the high speed on timber of smaller size. Subsequently, an individual steam engine drive was used where the speed of the lathe was controlled by a throttle operated by the cutter, and still later the slip ring motor was introduced, while at the present time there are a number of lathes operating with Reeves' variable speed transmissions for providing speed

control of the log. The double clutch pulley drive is not much better than the ordinary constant speed drive and, therefore, has not been followed to any extent in actual practice. The steam engine drive possesses a number of disadvantages in that it is difficult to get an engine which will start and stop as rapidly as it should in order to provide maximum production, while in addition, this type of drive requires a large amount of space which is often not available. The slip ring motor provides a speed range of 2 to 1, but since this type of motor has the same operating characteristics as the direct current series wound motor, namely, the speed of operation at any time depends entirely upon the load, the result is that in order to approximate a constant cutting speed it is necessary to continually adjust the speed control. The Reeves transmission provides a very good speed regulation, but owing to its design the cost of a proper transmission is excessive. Since the horse power required by a lathe running at constant cutting speed must essentially be constant horse power, the Reeves transmission is not suitable for use with veneer lathes, as such transmission is rated on a constant torque basis, namely, the horse power which it can transmit is proportional to the speed of the high speed shaft. It is, therefore, necessary in using a Reeves transmission to select one which will provide the proper horse power at low speed, but it will be quite apparent that the same transmission running at high speed will be capable of handling four or five times this amount of power.

Another disadvantage of the Reeves transmission is that it does not respond readily if it is desired to change the speed quickly, and in order to stop a lathe equipped with such transmission it is necessary to use a clutch in combination with a foot operated brake to absorb the energy in momentum.

In view of the characteristics of the shunt wound direct current motor it will be appreciated that such motor when used with a veneer lathe will more readily permit of the obtainance of the ideal drive referred to above. The speed of the shunt wound motor may be varied by changing the field strength, while at any given value of field strength the speed will remain constant regardless of the load. Furthermore, the motor can be so built that it will deliver the same horse power at any speed within the range for which it is designed, while in practice the field strength may be varied by introducing resistance into the shunt field circuit, with the result that as the resistance is increased the field current diminishes and the field strength decreases, causing the motor to run faster.

In order to more clearly bring out the advantages of the present invention than does

the foregoing discussion, a specific embodiment of the invention will be described hereinafter, such embodiment being illustrated in the accompanying drawings wherein

Fig. 1 is a transverse fragmentary section 70 through a veneer lathe embodying the invention, the well-known parts of the lathe being shown diagrammatically.

Fig. 2 is a fragmentary rear view of the lathe showing one of the end frames. 75

Fig. 3 is a diagrammatic showing of the wiring circuit and controls of the lathe.

Fig. 4 is a top plan view of the lathe.

It is not thought necessary to set forth herein a complete description of the operative parts of the veneer lathe since the same are so well known in the art and may be found on a majority of veneer lathes in use at the present time. Therefore the showing in the drawings of the lathe will be more or less schematic, while the description will only go into detail sufficiently to illustrate the location and mode of application of the invention, it being understood that the invention may be applied to any type of veneer lathe 90 and that so far as the present application relates to a specific form of lathe, it is simply by way of example.

The lathe comprises the usual end plates 10 together with a bed plate 11, which plates support the knife carriage mechanism and log supporting spindles, together with the driving connections for the same. As is understood, the log supporting spindles are arranged adjacent the front side of the lathe, one of such spindles being supported by each of the end plates 10 so that a log 12 may be supported by the spindles at its opposite ends and extend longitudinally of the lathe, it being understood that when the lathe is in operation the spindles rotate and, in turn, rotate the log.

The knife carriage comprises the knife bar 13 extending longitudinally of the lathe and supported at two places at its opposite ends. The first point of support for the opposite ends of the knife bar is formed by its circular tongue and groove connection, indicated at 14 by dotted lines, in the head block which, in turn, is slidably mounted in a guideway 15 in the end plates. This form of mounting for the knife carriage is well understood in the art and further reference thereto or illustration thereof is unnecessary. The other point of support for the opposite ends of the knife bar 13 is at the lower side thereof where the pin 16 is connected to a block 17 sliding in a slot 18 in a pitch-way frame 19. Although not illustrated herein it is customary to support the pitch-way frame so that it may be adjustably inclined in either direction, the form of such support usually being provided by means of eccentrics arranged at opposite ends of the frame whereby the eccentrics may be moved to

change the inclination of the frame, although under usual cutting conditions the slot 18 in the frame should incline downwardly from the back of the lathe toward the spindles.

The knife bar should be so mounted that the cutting edge of the knife 20 is in line with the centers of the circular tongue and grooves 14 in the head block, while the 10 tire knife bar pivots about this line during its feeding or receding movements. It is understood that the knife bar head blocks are each operatively connected with a feed screw 21, in turn connected through gearing 15 to a shaft 22 which is operatively associated with the driving mechanism for the lathe, whereby when the lathe is in operation the movement of the feed screws 21 will impart the feeding movement to the knife bar so as 20 to maintain the cutting edge of the knife in engagement with the log as the latter is rotated by the spindles and is accordingly reduced in diameter. The axial centers of the feed screws 21 should be in the same horizontal plane as the cutting edge of the knife so 25 the thrust thereof is put in line with the knife and chatter, due to worn parts, is eliminated.

From the foregoing description, together 30 with the well-known structural and operating characteristics of veneer lathes, it should be understood that when the lathe is in operation the log spindles are rotated and, of course, the log supported thereby, while the 35 knife bar head is fed toward the log and the cutting edge of the knife maintained in the proper cutting position with respect to the circumference of the log. As previously explained, the ideal driving arrangement for 40 a veneer lathe is one wherein the rotative speed of the log spindles and the log will be proportionately increased as the diameter of the log decreases due to the cutting of the veneer strip therefrom, so that the knife 45 will cut a veneer strip from the log at a constant rate or speed of production. The reason for this is quite evident when it is realized that the veneer strip will be cut from the log when the latter is of its maximum 50 diameter at a rate greatly exceeding the cutting rate when the log has been materially reduced in diameter. In order to provide for this ideal drive, the present invention 55 contemplates the utilization of a shunt wound direct current motor as the driving means for the lathe, such motor being illustrated diagrammatically at 23 in Fig. 3. Since the ideal drive may be obtained by accelerating the speed of the drive means in 60 the proper proportion as the log diminishes in diameter, and since a characteristic of the shunt wound direct current motor is that its speed may be varied by changing the field strength, it is proposed to introduce a resistance into the shunt field circuit and to con-

trol automatically the amount of resistance thrown into such circuit by means of mechanism operatively associated with the knife bar head and operated thereby as the head moves in its feeding movement to maintain the cutting edge of the knife in engagement with the log as the diameter thereof reduces. Since the motor may be caused to run faster as the field current and the field strength decreases, it will thus be necessary to increase 75 the resistance in the shunt field circuit in a predetermined amount as the log diameter decreases. To this end one of the end plates is formed to support, preferably at the rear side of the lathe, a suitable rheostat 24, such as the conventional pancake rheostat, this rheostat being arranged in the shunt field circuit.

A wheel 25 is mounted on the operating shaft 26 of the rheostat so as to engage a suitable member such as the leather face rack 27 operatively associated with the knife bar head. In operatively connecting the rack 27 to the knife bar head, a bar 28 supports the rack bar 27 and is bolted to a filler block 29 and to the knife bar head at one of its ends and is slidably supported at its other end by means of a guide 30 carried by the frame of the lathe. It will thus be seen that as the knife bar head moves forwardly as the log diameter diminishes that the rack bar 27 will move in direct proportion with the movement of the knife bar head and will cause rotation of the wheel 25 and operating shaft 26 of the rheostat, and, in turn, increase the resistance in the shunt field circuit of the motor. It is realized that it will be necessary to design the rheostat and the lathe so that different operating characteristics may be obtained thereby, but in order to clarify the invention and the mode of its operation a specific operating arrangement with respect to the rheostat and the drive for the lathe will be set forth herein by way of example.

Supposing that it is desired to provide a constant cutting speed between log diameters of 28" maximum and 7" minimum, the motor would be designed to provide constant horse power from 250 to 1000 R. P. M. and would be so geared to the log spindles that the corresponding log speeds would be 30 R. P. M. minimum and 120 R. P. M. maximum. It will be seen that when the knife is in position for cutting on a 28" diameter circle or larger, the spindles and the log would be revolving at 30 R. P. M. As the knife bar advances toward the spindles the rack 27 engages the wheel 25 and operates the rheostat, which should be so designed as 110 to throw resistance into the shunt wound circuit in an amount resulting in the product of the log diameter by the R. P. M. of the log spindles being constant between 28" diameter 115 and 7" diameter. Thus it will be seen that 120 125 130

when the diameter is 28" and the spindles are rotating at 30 R. P. M., the product will be 840, while after the log has been reduced to 21" in diameter and the rotation of the 5 spindles accelerated to 40 R. P. M. the product will still be 840. In the same way, when the diameter has been reduced to 14" and the speed of the spindles accelerated to 60 R. P. M., or just twice the speed at 28" diameter, the product will still be 840. The speed 10 of the log spindles may thus be increased or accelerated in this proportion until at 7" diameter, which is the minimum for the example given, the maximum speed of the 15 spindles, namely, 120 R. P. M., is reached.

It is understood that the above description applies to one particular case and that since 20 motors with a speed variation of as much as 6 to 1 by field control, are available, it would 25 be possible to provide constant cutting speed between 42" diameter maximum and 7" diameter minimum, or if larger logs are used the range with the 6 to 1 motor could be made 48" maximum to 8" minimum or 54" maximum to 9" minimum, and so on.

In addition to the foregoing desirable manner of providing constant cutting speed for the veneer strips, it is possible by using the 20 shunt wound direct current motor to have the entire control of the motor through push buttons, by means of automatic starting equipment. The control push buttons are shown in Fig. 3 at 31 and 32 together with the 25 circuits therefor, but since any conventional automatic starting equipment may be used in the circuit, the acceleration current relays, overload protection devices and the like, are not shown. Since defects occur in the logs 30 such as wind-shakes, knots and the like, it is necessary at certain times to reduce the speed of the log to a minimum, and for this purpose a push button 33 is provided which may close a circuit shunting around the rheostat resistance and throwing full field on the 35 motor, thus causing the latter to run at its slowest speed. It is often necessary in rounding up a rough log to cause the log to revolve at any predetermined speed within the limits of the motor and a suitable switch 34 is provided 40 for this purpose; thus if the circuit were designed to cause the log to revolve at 60 R. P. M. for rounding up, the moment the switch was released the driving motor would 45 automatically assume a speed corresponding to the cutting speed for which the equipment is designed. In order to stop the lathe practically instantaneously, a dynamic brake 50 on the motor may be thrown by depressing 55 the stop button 32.

It should be understood that the invention 60 is susceptible in its broad aspects of being used with various types of lathes in different modes of application and that the embodiment herein shown, together with the spe-

cific wiring circuit, is merely by way of illustration and that the invention is to be limited thereto only so far as the scope of the claims so limits it.

Having thus described my invention, I 70 claim:

1. In a veneer lathe, rotatable spindles adapted to support a log, a motor for operating said spindles, means for cutting veneer strips from said log and automatically adjustable to compensate for variations in the diameter of the log, and means for automatically controlling the speed of operation of said motor, said means including a rheostat in the motor circuit and having an operating 80 shaft provided with a wheel, and a rack bar connected to said cutting means and engaging said wheel.

2. In a veneer lathe, rotatable spindles adapted to support a log, a shunt wound direct current motor for operating said spindles, means for cutting veneer strips from said log and automatically adjustable to compensate for variations in the diameter of the log, and means for automatically accelerating the speed of operation of said motor in proportion to the diminution of the diameter of the log, said means including a rheostat arranged in the shunt field circuit of the motor and having an operating shaft 90 provided with a wheel, and a rack bar operatively engaging said wheel and connected to said cutting means to move therewith.

3. In a veneer lathe, rotatable spindles adapted to support a log, a driving means 100 for said spindles having a constant operating speed irrespective of load, means for cutting veneer strips from the log and automatically adjustable to compensate for variations in the log diameter, means operatively associated with said last named means for automatically accelerating the speed of operation of the driving, and means operable independently of or in conjunction with said last named means for quickly decelerating or accelerating the speed of operation of said driving means.

In testimony whereof, I hereunto affix my signature.
